Patented Aug. 8, 1899.

H. C. PORTER.

BATTERY PLATE.

Application filed July 1, 1899.

UNITED STATES PATENT OFFICE.

HENRY C. PORTER, OF CHICAGO, ILLINOIS, ASSIGNOR OF ONE-HALF TO
THE OWEN H. FAY LIVERY COMPANY, OF SAME PLACE.

DESIGN FOR A BATTERY-PLATE.

SPECIFICATION forming part of Design No. 31,366, dated August 8, 1899.

Application filed July 1, 1899. Serial No. 722,605. Term of patent 7 years.

To all whom it may concern:

Be it known that I, HENRY C. PORTER, a citizen of the United States, residing at Chicago, in the county of Cook and State of Illinois, have invented a certain new and useful 5 Design for Battery-Plates, of which the following is a specification.

My design is illustrated in the accompanying drawings, in which—

10 Figure 1 represents a perspective view of a battery-plate embodying my design. Fig. 2 represents a detailed section thereof.

The leading feature of my design consists of a generally rectangular open frame having 15 parallel bars extending between the longer sides of said frame, said parallel bars having W-shaped grooves in the opposite inner faces thereof, while the frame-bars have correspondingly-shaped grooves in their inner 20 faces.

Referring now to the drawings, my battery-plate consists of the rectangular frame composed of the end bars A B and the side bars C, the side bars being of greater length than the 25 end bars and all of said bars being substantially rectangular in cross-section and having plain outer faces both as to their sides and edges, but having W-shaped grooves in their inner faces. Between the side bars C extend 30 a series of parallel bars D, spaced regularly at

distances apart slightly greater than the width of the bars. By reason of the bars D extending between the bars C, flush therewith, at opposite sides of the plate the bars D each have two outer and two inner faces, the two 35 inner faces, as the plate is shown in the drawings, being the upper and lower faces. Each upper and lower face of each bar, as more particularly illustrated in Fig. 2, has a W-shaped groove E therein, the grooves on the opposite 40 inner side of each bar being reversely arranged, so that with the plate in the upright position shown in Fig. 1 the groove in the upper face of each bar will be a W-shaped groove, while the groove in the lower face of 45 each bar will be an M-shaped groove. The peculiar shape of these grooves in the frame-bars C and the cross-bars D, together with the arrangement of the bars in the frame, give to the plate a characteristic and distin- 50 guishing appearance.

Having thus fully described my invention, what I claim, and desire to secure by design Letters Patent, is—

The design for a battery-plate as herein 55 shown and described.

HENRY C. PORTER.
